UNITED STATES PATENT OFFICE.

CHARLES L. BASTIAN, OF CHICAGO, ILLINOIS.

DRIVING MECHANISM FOR CARBONATING-MACHINES.

1,195,765.

Specification of Letters Patent. Patented Aug. 22, 1916.

Application filed April 19, 1915. Serial No. 22,260.

To all whom it may concern:

Be it known that I, CHARLES L. BASTIAN, a citizen of the United States, residing at Chicago, in the county of Cook and State of Illinois, have invented certain new and useful Improvements in Driving Mechanism for Carbonating-Machines, of which the following is a specification.

This invention relates in general to automatic machines for carbonating liquids and more specifically to the means whereby the prime mover, which furnishes power to the machine, is allowed an appreciable starting interval before the full load of the machine is applied thereto.

The device is particularly adapted for use in connection with electrically driven carbonating machines in which current is automatically supplied to the motor at intervals, after the supply of carbonated liquid has been depleted. In such machines, which are now well-known in the art, the full current is turned into the motor whenever it becomes necessary to carbonate additional quantities of liquid, no provision being made to supply the current gradually by means of resistance coils following the usual practice. It is well-known to those versed in the electrical art that, particularly where alternating current motors are used, unless a motor of considerably greater power than that required for the load is used, the rush of current into the motor in starting is sufficient to dim the lamps in the same circuit noticeably and to blow the fuses frequently, entailing considerable annoyance and labor. Furthermore, fire underwriters and power companies will no longer permit the installation of motors under these conditions. Obviously the use of a larger motor involves an unwarranted expense and hence a simple and effective means of relieving the motor in starting is desirable.

It is the object of my invention to provide a simple mechanism consisting of a minimum number of relatively inexpensive parts, whereby a motor is automatically relieved from the full load for an appreciable interval after starting wherein the motor has an opportunity to start and attain considerable momentum.

A further object of my invention is the provision of an automatic machine for carbonating liquids in which the load is applied gradually to a motor, which receives the full current when started.

Further objects and advantages of the invention will be apparent as it is better understood by reference to the following specification when read in connection with the accompanying drawing in which—

Figure 1 is a side elevation of a carbonating machine, showing the means installed for relieving the motor from the full load when started; Fig. 2 is an enlarged elevation partially in section of the load-relieving means, and Fig. 3 is a vertical section on the line 3—3 of Fig. 2.

Referring to the drawings, 1 indicates the agitating tank of a carbonator, which may be of any suitable form and construction and provided with the usual gage glass 2 and pressure indicator 3, such tanks being well-known in the art. A shaft 4 extends through the tank, being mounted in suitable stuffing boxes in the walls thereof and provided with agitator blades (not shown). A sprocket 5 is secured to one end of the shaft 2 and is connected to a counter-shaft 6, suitably mounted above the tank 1, by means of a chain 7, disposed about a sprocket 8 secured to the shaft 6. A crank disk 6' is secured to the opposite end of the shaft 6 and actuates the piston 7' of a pump 8' through the connecting rod 9', one end of which is secured to the crank pin 10' mounted on the disk 6'.

Loosely mounted on the shaft 6 is a gear 9 which meshes with a pinion 10 on the shaft 11 of the motor 12, which is supplied with current at intervals through the conductors 13. The gear 9 is provided with a hub 14 having a lug or tooth 15 formed integrally therewith and adapted to operatively engage a lug or tooth 16 formed integrally with the collar 17 keyed to the shaft 6. When the lugs 15 and 16 are disposed in coöperative relation the shaft 6 will be driven by the gear 9, which is in turn actuated by the motor 12.

To normally maintain the lugs 15 and 16 in separated relation when the machine is idle I provide a spiral spring 18 secured at its inner end to the collar 17, fast to the shaft 6, and at its opposite end to a pin 19, mounted in one of the spokes of the gear 9 and disposed in parallel relation with the shaft 6. The spring 18 tends normally to separate the lugs 15 and 16, as indicated in the drawings, and maintains the lugs in the positions indicated when the machine is at rest. When the supply of carbonated water has been depleted the circuit to the motor 12 is auto-

matically closed in a manner well-known in the art and the motor starts to operate. The pressure which the motor 12 must overcome in starting the pump 8' is approximately 200 pounds and if no means for relieving the motor temporarily from the load is provided a quantity of current nearly ten times that required to operate the machine when in motion will be required. As will be noted in Figs. 1 and 2 of the drawing, the reduction between the pinion 10 and the gear 9 is relatively great, so that a considerable number of revolutions of the shaft 11 is required to move the gear 10 through a relatively short distance. During the starting operation the spring 18 allows a considerable movement of the gear 9 before the lugs 15 and 16 engage and the inertia of the mechanism is gradually overcome, so that, when the lugs 15 and 16 engage, the motor 12 has attained sufficient momentum to safely take up the full load of the machine and the danger of blowing fuses or otherwise injuring the motor is obviated.

It will be apparent that various changes may be made in the form, construction and arrangement of the parts within the scope of the appended claims without departing from the spirit and scope of the invention, or sacrificing any of its material advantages, the form hereinbefore described being merely a preferred embodiment thereof.

I claim:

1. In an apparatus for carbonating liquids, the combination of a shaft, a gear loosely mounted on said shaft, a motor for actuating said gear, a clutch element carried by said gear, a complementary clutch element secured to said shaft and spaced from said gear longitudinally of said shaft, and a spring connected at either end to said gear and complementary clutch element respectively, whereby said clutch elements are normally separated when said gear is at rest and said gear is allowed to move through an appreciable distance before said clutch elements engage.

2. In an apparatus for carbonating liquids, the combination of a shaft, a driving

member loosely mounted on said shaft, 50 means for actuating said driving member, a driven member secured to said shaft and spaced laterally from said driving member, clutch elements on said driving and driven members, whereby the latter is positively actuated by the former, and resilient means secured to said members, whereby said elements are normally separated when said members are at rest and said driving member is allowed to move through an appreciable distance before said elements engage.

3. In an apparatus for carbonating liquids the combination of a shaft, a gear loosely mounted on said shaft and provided with a hub, a motor for actuating said gear, 65 a clutch element on said hub, a complementary clutch element secured to said shaft adjacent the hub of said gear, and a spring connected to said gear and complementary clutch element, whereby the clutch element 70 on the hub of said gear is maintained in spaced relation with said complementary clutch element when said gear is at rest and said gear is allowed to move through an appreciable angular distance before said 75 clutch elements engage.

4. In an apparatus for carbonating liquids, the combination of a shaft, a gear loosely mounted on said shaft and provided with a hub, a motor for actuating said gear, 80 a clutch element on said hub, a complementary clutch element secured to said shaft adjacent the hub of said gear, a pin projecting laterally from said gear in the direction of said complementary clutch element, 85 and a spring connected to said pin and complementary clutch element, whereby the clutch element on the hub of said gear is maintained in spaced relation with said complementary clutch element when said 90 gear is at rest and said gear is allowed to move through an appreciable angular distance before said clutch elements engage.

CHARLES L. BASTIAN.
